PILLOWCASE

William L. M. Clark, Clayton, Mo., assignor to
W. L. M. Clark Inc., St. Louis, Mo., a corpora-
tion of Missouri

Application August 28, 1950, Serial No. 11,957

Term of patent 3½ years

(Cl. D92—26)

To all whom it may concern:

Be it known that I, W. L. M. Clark, a citizen of the United States, residing in the city of Clayton and State of Missouri, have invented a new, original, and ornamental Design for a Pillowcase, of which the following is a specification, reference being had to the accompanying drawing forming part thereof.

In the drawing,

Fig. 1 is a plan view of the top of one end of a pillowcase showing my new design, and

Fig. 2 is a view of the under side of said end of said pillowcase.

The pillowcase is of conventional shape, part of which pillowcase has been omitted for convenience in illustration.

I claim:

The ornamental design for a pillowcase, substantially as shown and described.

W. L. M. CLARK.
